UNITED STATES PATENT OFFICE

PERRY WHITING, OF LOS ANGELES, CALIFORNIA

STUCCO BUILDING CONSTRUCTION

Application filed November 17, 1930. Serial No. 496,173.

This invention relates to stucco building construction and, more especially, to the construction around the openings in the building as, for example, the window and door openings.

One of the principal objects of this invention is to provide for a wall of a thickness that will give an effect of solidity to the building, though stucco is employed as the finish on the exterior of the building. In other words, the invention affords excellent construction for stucco buildings when it is desired to produce a deep window or door recess.

Another important object is to accomplish the foregoing and at the same time provide for proper drainage of water from the stucco over the opening so as to insure against such water running between the stucco and the window-frame.

Another important object is to accomplish the appearance of solidity by the employment of a minimum amount of lumber.

Other objects and advantages will appear in the subjoined detailed description.

The accompanying drawings illustrate the invention:

Figure 1 is an exterior view of a stucco building construction embodying the invention, portions of the wall being broken away to contract the view.

Figure 2 is an enlarged broken vertical section on the line indicated by 2--2, Fig. 1.

Figure 3 is an enlarged broken horizontal section on the line indicated by 3--3, Fig. 2.

Referring to the drawings, window jambs are shown at 5 and a windowsill at 6, and these members, together with a pair of horizontally extending members 7, 8, surround a window opening 9 in which may be mounted the window sash 10 in a manner well understood in the building art. A sash stop is indicated at 11, a screen guide at 12 and a screen stop at 13. The inner face of the member 7 overlaps an edge face of the member 8 and said members form a right angle within which is a roller screen 14. Secured to the member 8 is an interior head casing 15.

Extending across the top of the opening 9, above the members 7, 8, are a series of

horizontal frame members 16, 17, 18 of progressively greater thickness and width from the bottom one to the top. Also extending horizontally below the opening 9, beneath the sill 6, is a series of frame members 19, 20 and 21, of progressively greater width and thickness from the uppermost to the lowermost.

At each side of the opening 9, outside of the jamb 10, is a series of vertically extending frame members 22, 23, and 24 of progressively greater width and thickness from the inner to the outer. These members 16 to 24, inclusive, are secured together and to other frame members of the building, not shown, in a manner well understood in the building art. The inner edges of the members 16 to 24, inclusive, are flush with one another and the lath 25 of the inside wall 26 is secured to said members.

The sill 6 and jambs 10 have angular recesses 27 in their outer edges to receive the foundation 28 to which the stucco 29 of the exterior wall adheres and said stucco is extended into the recesses 27. In the outer face of the member 7 is an angular recess 30 to receive the foundation 28 and stucco 29 of the exterior wall, said stucco extending into the recess 30. The recess 30 has a downwardly and inwardly slanting wall 31, a substantially vertical wall 32 and a downwardly and outwardly sloping wall 33.

A metal drip strip 34 is secured by fastening means 35 to the wall 33 and extends from end to end of the recess 30. The strip 34 has a width greater than the width of the wall 33 so as to have a portion 36 that projects outwardly and downwardly from the outer face of the member 7 and stucco 29.

The foundation 28 and stucco 29 extend aslant from the recesses 27, 30 past the outer edges of the members 16, 17, 19, 20, 22, and 23 to form sloping exterior wall portions 37 at an angle to the plane of the opening 9. From the outer ends of the sloping wall portions 37, the exterior wall extends in portions 38 that lie in a vertical plane.

The foundation 28 is secured to the outer edges of the members 18, 21, 24 and to the wall of the recesses 27, 30, as indicated at 39.

The construction and operation of the invention will be apparent from the foregoing. It will be seen that walls of a substantial thickness or depth may be formed so as to provide for deep recesses for window and door openings.

It will also be seen that these recesses are amply protected against the entrance of water, since any water flowing down the upper wall portion 37 will be caused, by the strip 34, to drip onto the lower wall portion 37, thereby causing said water to flow outwardly and downwardly, thereby insuring against water entering or passing to the interior plaster between the stucco and the window or door framing, as the case may be.

I claim:

1. A stucco building construction comprising a sill, a horizontally extending member above and spaced from the sill and provided with a recess extending lengthwise in its outer face, jambs connecting the sill and said member, a drip strip extending along the bottom of the recess and projecting aslant downwardly and outwardly therefrom, and a wall having a downwardly and inwardly sloping portion extending into the recess and onto the drip strip and secured to said member.

2. A stucco building construction comprising a sill, a horizontally extending member above and spaced from the sill and provided with a recess extending lengthwise in its outer face, jambs connecting the sill and said member, a series of horizontal frame members above the first mentioned member of progressively greater width from the lower one to the upper one, a drip strip extending along the bottom of the recess and projecting aslant downwardly and outwardly therefrom, and a wall having a vertical portion secured to the outer edge of the wider frame member, said wall having a portion sloping downwardly and inwardly past the outer edges of the narrower frame member and into the recess and onto the drip strip and secured to said first mentioned member.

3. A stucco building construction comprising a sill, a horizontally extending member above and spaced from the sill and provided with a recess extending lengthwise in its outer face, jambs connecting the sill and said member and each provided with a recess extending lengthwise in its outer face, a drip strip extending along the bottom of the first mentioned recess and projecting aslant downwardly and outwardly therefrom, and a wall having a downwardly and inwardly sloping portion extending into the first mentioned recess and onto the drip strip and secured to said member, said wall having outwardly and laterally sloping portions extending into the second mentioned recess and secured to the jambs.

4. A stucco building construction comprising a sill provided with a recess extending

lengthwise in its outer edges, a horizontally extending member above and spaced from the sill and provided with a recess extending lengthwise in its outer face, jambs connecting the sill and said member, a drip strip extending along the bottom of the second mentioned recess and projecting aslant downwardly and outwardly therefrom, and a wall having a downwardly and inwardly sloping portion extending into the second mentioned recess and onto the drip strip and secured to said member, said wall having a downwardly and outwardly sloping portion extending into the first mentioned recess and secured to the sill.

5. A stucco building construction comprising a sill provided with a recess extending lengthwise in its outer edge, a horizontally extending member above and spaced from the sill and provided with a recess extending lengthwise in its outer face, jambs connecting the sill and said member and each provided with a recess extending lengthwise in its outer face, a drip strip extending along the bottom of the second mentioned recess and projecting aslant downwardly and outwardly therefrom, and a wall having a downwardly and inwardly sloping portion extending into the second mentioned recess and onto the drip strip and secured to said member, said wall having a downwardly and outwardly sloping portion extending into the first mentioned recess and secured to the sill, and said wall having outwardly and laterally sloping portions extending into the third mentioned recesses and secured to the jambs.

6. A stucco building construction comprising a sill, a horizontally extending member above and spaced from the sill, jambs connecting the sill and said member, a drip strip secured to the outer face of said member and projecting aslant downwardly and outwardly therefrom, a series of horizontal frame members above the first mentioned member of progressively greater width from the lower one to the upper one, a series of vertical frame members outside of the jambs of progressively greater width from the inner to the outer one, a wall having portions secured to the jambs and said member and sloping outwardly therefrom past the outer edges of the narrower frame members and onto the drip strip and secured to said first mentioned member, said wall having a vertical portion secured to the outer edges of the wider frame members.

Signed at Los Angeles, California, this 1st day of November, 1930.
